F. W. Freeman
His ATTORNEY

Patented June 5, 1928.

UNITED STATES PATENT OFFICE.

WILLIAM H. ROSE, OF JERSEY CITY, NEW JERSEY.

WIND DEFLECTOR.

Application filed May 5, 1927. Serial No. 188,892.

My invention relates to wind deflectors and refers particularly to devices of this character adaptable for use with open windows.

5 One of the objects of my invention is a wind deflector which may be readily and firmly attached either fixedly or removably to a window frame.

In the accompanying drawings illustrating modified forms of the device of my invention, similar parts are designated by similar numerals.

Figure 1 is a perspective view of one form of my device without the fastening means.

15 Figure 2 is an enlarged perspective view of one portion of Figure 1.

Figure 3 is a view showing one end of my device attached to a window frame.

Figure 4 is a front view of the fastening means shown in Figure 3.

Figure 5 is a cross-section through the line 5—5 of Figure 4.

Figure 6 is a cross-section of a modified form of fastening means.

25 Figure 7 is a cross-section of a modified form of fastening means.

Figure 8 is a front view of a modified form of fastening means.

Figure 9 is a cross-section through the 30 line 9—9 of Figure 8.

Figure 10 is a cross-section of a modified form of fastening means and deflector end.

Figure 11 is a cross-section of a modified form of fastening means and deflector end.

35 Figure 12 is a cross-section of a modified form of fastening means.

Figure 13 is a cross-section of a modified form of fastening means.

The particular form of my device shown 40 in the accompanying Figures 1 to 5 inclusive comprises a sheet of corrugated cardboard scored along the lines A—A and B—B, to allow of the formation of the deflector plate 15 and the two end members 16 and 16. Within each lower end portion of the plate 15 and spaced from the end thereof is a slot 17, the length of the slot being slightly greater than the width of the fastening means described later. The fastening 45 means comprises a U-shaped piece of metal 18, one edge of which is bent inwardly to form a guide and holding member 19. One side 18 of the guide 19 has a plurality of holes 20, 20, while in alignment with said holes 20, 20 there are a plurality of longer holes 21, 21.

The operation of the device is as follows:

The fastening means 18 is fixedly attached to the window frame 22 by means of a screw 60 23 through each hole 20, access for inserting the screw being through a hole 21. A similar fastening means 18 is fixedly attached to the opposite side of the window frame. In order to apply the deflector the ends 16, 16 65 are passed downwardly between the two branches of the U-shaped fastening member 18, the slots 17, 17 allowing of this movement, and the guide 19 moving along a groove 24 within each end member 16, thus 70 both guiding the movement of the ends 16, 16 and acting as a holding means to protect the outward disengagement of the device while the device may be readily removed if desired.

75 The modified form of fastening means shown in Figure 6 has two holes 20, 20 of the same size and in the application of this form, the deflector end and the fastening means are fixedly attached to a window 80 frame by a screw passing therethrough.

The modified form of fastening means shown in Figure 7 is similar to that of Figure 6 except that it has two staggered prongs 19, 19, movable within two grooves 24, 24, of 85 the end 16.

The modified form shown in Figures 8 and 9 comprises a U-shaped member 18 without any prongs, and with aligned holes 20, 20 90 of the same size.

In the modified forms shown in Figures 10 and 11, the end 16 has an enlarged portion 25 fixedly attached thereto, thus overcoming the necessity of grooves in the end 16. Figure 10 has holes of different size 95 while the holes in Figure 11 are of the same size.

In Figure 12, the fastening member 18 is cemented at 26 to the wooden window frame 22, thus overcoming the necessity of screw 100 fastening means.

In Figure 13, a wooden strip 27 is cemented at 28 to the metal window frame 22. The fastening means 18 is attached to the window strip 27 by means of screws 29, 29, and 105 30, the deflector end 16 attached by the screw 30.

By spacing the slots 17, 17 from the folding edges A—A and B—B, the folding, or bending of the ends 16, 16 may be more effectively accomplished and the tearing or 110 breaking of the device is prevented.

The construction also allows of the de-

vice being brought into close contact with the window frame.

It is to be noted that the length of the slots 17, 17, must be at least equal to the width of the fastening means 18 in order to allow of the passage of the ends 16, 16 therethrough.

While I have described my device as formed from corrugated cardboard, it is evident that it may be made of fiber board, metal or other suitable material, neither need it be of one piece as shown.

I do not limit myself to the particular size, shape, number, arrangement or material of parts as shown and described as these are given simply as a means for describing the device of my invention.

What I claim is:

1. In a wind deflector, in combination, a front member having an upwardly extended slot in each lower end portion, an angularly positioned end member carried by each end of the front member, and two U-shaped fastening means a portion of each of which is capable of passing through a said slot and capable of slidable movement along the end member.

2. In a wind deflector, in combination, a front member having an upwardly extended slot in each lower end portion, an angularly positioned end member carried by each end of the front member, each end member having a groove therein, two U-shaped fastening means a portion of each of which is capable of passing through a said slot and capable of slidable movement along the end member and an inwardly extended prong carried by each U-shaped member capable of movement within a said end member groove.

3. In a wind deflector, in combination, a front member having an upwardly extended slot in each lower end portion, an angularly positioned end member carried by each end of the front member, two U-shaped fastening means a portion of each of which is capable of passing through a said slot and capable of slidable movement along the end member to position the deflector in angular position with respect to a window frame to

which the U-shaped member is attached and means for fastening the U-shaped member to a window frame.

4. In a wind deflector, in combination, a front member having an upwardly extended slot in each lower end portion, an angularly positioned end member carried by each end of the front member, two U-shaped fastening means a portion of each of which is capable of passing through a said slot and capable of slidable movement along the end member to position the deflector in angular position with respect to a window frame to which the U-shaped member is attached and an inwardly extended prong carried by each U-shaped member.

5. In a wind deflector, in combination, a front member having an upwardly extended slot in each lower end portion, an angularly positioned end member carried by each end of the front member, and two U-shaped fastening means a portion of each of which is capable of passing through a said slot and capable of slidable movement along the end member to position the deflector in angular position with respect to a window frame to which the U-shaped member is attached the sides of the U-shaped member having a plurality of aligned holes.

6. In a wind deflector, in combination, a front member having an upwardly extended slot in each lower end portion, an angularly positioned end member carried by each end of the front member, each end member having a groove therein, two U-shaped fastening means a portion of each of which is capable of passing through a said slot and capable of slidable movement along the end member to position the deflector in angular position with respect to a window frame to which the U-shaped member is attached the sides of the U-shaped member having a plurality of aligned holes and an inwardly extended prong carried by each U-shaped member capable of movement within a said end member groove.

Signed at New York city in the county of New York and State of New York this 4th day of May, 1927.

WILLIAM H. ROSE.
